UNITED STATES PATENT OFFICE.

OLIVER C. DENNIS, OF WILMETTE, ILLINOIS.

DESIGN FOR A COMBINED RADIO LOUD SPEAKER AND BOOK END.

Application filed April 5, 1926. Serial No. 17,189. Term of patent 3½ years.

To all whom it may concern:

Be it known that I, OLIVER C. DENNIS, a citizen of the United States, residing at Wilmette, in the county of Cook and State of Illinois, have invented a new, original, and ornamental Design for a Combined Radio Loud Speaker and Book End, of which the following is a specification, reference being had to the accompanying drawing, forming a part thereof.

The drawing is a perspective of a combined radio loud speaker and book end showing my new design.

I claim:

The ornamental design for a combined radio loud speaker and book end, as shown.

OLIVER C. DENNIS.
